UNITED STATES PATENT OFFICE.

THEODORE T. JANIS, OF CHICAGO, ILLINOIS.

TEMPLLET-FILING JAWS.

1,415,573.

Specification of Letters Patent. Patented May 9, 1922.

Application filed March 24, 1919. Serial No. 284,551.

To all whom it may concern:

Be it known that I, THEODORE T. JANIS, a citizen of the United States, residing at Chicago, county of Cook, State of Illinois, 5 have invented a certain new and useful Improvement in Templet-Filing Jaws, and declare the following to be a full, clear, and exact description of the same, such as will enable others skilled in the art to which it 10 pertains to make and use the same, reference being had to the accompanying drawings, which form a part of this specification.

In making small metal templets, the tool maker lays them out on blank pieces and 15 then files to the marks while holding the pieces in a vise. In filing, as a scratched line is approached, a burr is formed which obscures the line and makes it necessary that great care be taken in order to secure accuracy of work. 20

The object of the present invention is to produce a simple and novel device in which templet blanks may be readily positioned and be firmly held in such a way that the 25 workman need only file into a blank until the file touches a hardened limiting surface in the device, in order to be certain that exactly the right amount of material has been removed.

30 A further object of the present invention is to produce a device of the character just described which will serve also as a base from which any desired angle may be conveniently and accurately measured so that 35 an edge of a templet may quickly be filed or ground so as to lie at any desired angle with respect to some other edge.

40 A further object of the present invention is to produce a simple and novel templet holder which is adapted to be held in a vise or other supporting device or in a chuck, mechanical or magnetic.

45 The various features of novelty whereby my invention is characterized will herein- 50 after be pointed out with particularity in the claims; but, for a full understanding of my invention and of its objects and advantages, reference may be had to the following detailed description taken in connection with the accompanying drawing, wherein:

Figure 1 is a side view of a device arranged in accordance with a preferred form of my invention;

Fig. 2 is a view of the opposite side of the

device from that shown in Fig. 1 and showing an attachment which is omitted in Fig. 1;

Fig. 3 is a top plan view;

Fig. 4 is a section taken approximately on line 4—4 of Fig. 3;

Fig. 5 is a section taken approximately on line 5—5 of Fig. 3;

Fig. 6 is a section taken approximately on line 6—6 of Fig. 3, the block appearing above one of the bars in Fig. 3 being omitted from Fig. 6.

Fig. 7 is a section taken approximately on line 7—7 of Fig. 3;

Fig. 8 is a section taken on line 8—8 of Fig. 3, only one end of the device being 70 shown, and there being a templet arranged in the device;

Fig. 9 is a view similar to Fig. 8 showing a different form of templet from that illustrated in Fig. 8; and

Fig. 10 is a view similar to Figs. 8 and 9, showing a still different type of templet.

Referring to the drawing, 1 and 2 represent two bars of extremely hard steel each of which has at least two contiguous faces made 80 perfectly flat and arranged at right angles to each other. Preferably each bar is made accurately rectangular in cross section as this greatly widens the field of use of the device.

85 One of the bars has projecting from the side thereof a pair of aligning pins 3, 3, rigidly connected therewith, while the other device has holes, 4, accurately fitting the pins. The pins are arranged at right angles 90 to the face from which they project and therefore when the bars are moved from and toward each other they always remain parallel.

95 Suitable means are provided for moving the bars from and toward each other and exerting a force which will permit them to be clamped tightly upon a piece of work; such means being preferably so designed as not to obstruct the outer surfaces of the device 100 when in use. In the arrangement shown, there are three screws, 5, 6 and 7, extending through one of the bars and into the other in parallelism with the aligning pins. The heads of the screws are preferably countersunk in one of the bars and the screws are 105 preferably made so short that when the bars are clamped upon the thinnest blank, in con-

nection with which it will be used in practice, the ends of the screws will not project beyond the outer side face of the other bar. The screws are conveniently placed along 5 the longitudinal center of the bars. When the device is placed in a vise or other holder which is not adapted for precision work, there might be a tendency to tilt the bars relatively to each other and, in order to prevent this, I make use of set screws 8, Figs. 1 and 7, which are screw threaded through 10 one of the bars and engage with the inner side face of the other bar; thus serving as abutments or stops which may be accurately 15 adjusted after the work has been clamped in the device, thus guarding against any tilting of the bars if the device is subsequently placed in a holding support of some kind. In the arrangement shown, there are two of 20 these set screws which may either be placed in the bar 1 as shown in Fig. 1 or in screw threaded openings, 9, in the bar 2 as shown in Fig. 2; the two sets of openings being differently located with respect to the length 25 of the bars, so that the set screws may be placed where they will not interfere with the work being held at any given time.

After a templet blank has been properly laid out, it may be clamped in the device so 30 as to bring the lines to which the blank is to be filed, one after another, exactly in the plane of the upper faces of the bars. The bars being made so hard that they will resist the action of a file, and the upper face and 35 the inner side face of each bar meeting in a sharp corner forming the apex of an exact right angle, it will be seen that after the blank has been placed in position, the workman needs only to file until the tool rests 40 upon the hardened bars in order to finish an edge of the templet accurately to a line and accurately square with the side faces of the templet.

It may sometimes be desirable to be able 45 to file on two edges of a blank arranged at right angles to each other or possibly at some other angle. In order to permit this to be done, an additional block, 10, may be provided; said block being detachable from 50 the bars and being adapted to be adjusted along one or both of them. In the arrangement shown, each of the bars has in the upper edge a groove, 11, extending lengthwise thereof along the center. The block, 10, is 55 made of the same thickness as each of the bars and is provided with a tongue, 12, as best seen in Fig. 8, adapted to enter either of the grooves. An elongated slot, countersunk at the top as indicated at 13, as best shown 60 in Fig. 3, extends vertically through the block which is rigidly fastened in place by means of a screw, 14, extending through the slot into one of the bars and having its head lying in the countersunk portion of the 65 slot. Each of the bars is provided with a

series of screw threaded holes, 15, in its upper edge; the screw 14 being adapted to be inserted in any one of these holes.

In the arrangement shown, one end of the block, as indicated at 16, is finished so that 70 it will be accurately at right angles to the top surface of the bars while the other end, as indicated at 17, is inclined at some suitable angle as, for example, forty five degrees.

For many purposes the block is not needed. However, when a templet such as shown, for example, at 18 in Fig. 8 is to be filed, the block may be placed in position on one of the bars and the templet blank be then clamped in place so that one edge of the arm 80 19 projects slightly above the upper surface of the bars while one edge of the arm 20 of the blank projects slightly beyond the square end of the block. The two edges may thus be filed without shifting the blank. 85 This expedient not only saves time but it permits a perfectly sharp corner to be obtained between the horizontal and the vertical edges of the templet, without danger of marring either edge. Without the block, it 90 would be necessary first to file the edge on the arm 19 and then the edge on the arm 20 with the arm 19 projecting upwardly and in danger of being marred by the file working 95 on the arm 20.

In case the arm 20 lay at an angle of forty-five degrees to the arm 19, then the block could be reversed so as to permit the edge 17 to be used as the guiding edge during the filing operation.

The block may also be made to serve simply as a measuring device for setting a projecting part at a right angle to the upper surface of the bars or at an angle corresponding to the inclination of the end 17.

Even though the block be not employed, the upper faces of the bars may be used as a base from which to measure any given angle. Thus, if the purpose is to make the two arms of the templet 18 lie at a given 100 angle with respect to each other, a measuring instrument may be placed on top of the bars and the upwardly-projecting arm of the work be adjusted thereby.

In Fig. 9 another use of the device is illustrated. The templet, 21, is intended to have a notch, 22, in one or both ends. The end to be notched is first finished in the manner heretofore explained, and the templet is then raised a distance exactly equal to the depth of the notch to be formed; it being possible to make the measurement accurately from the upper surface of the bars. The workman need then only file into the projecting end of the templet until the tool touches the bars.

In Fig. 10 there is illustrated a templet, 24, of such size that one of the clamping screws must be removed in order to make room for the work; the screw that is removed being the one in the center. It will 130

be evident that where the work takes still other forms it might be necessary to remove some other clamping screw or shift the holding screws from one bar to the other.

- 5 It will be seen that my improved device provides means for conveniently holding work of various kinds which must be accurately finished by filing or grinding, permitting the filing or grinding to be quickly 45
 10 done, and affording a variety of surfaces from which accurate measurements of distances and angles may be made. It will also be seen that the device can conveniently be held in a vise or chuck and, by placing it 15 against a flat face plate, the work will be accurately held at right angles to the face plate. Another use to which the device can be put is to clamp it to an angle plate while holding a piece of work; any one of three 20 sides and, in some cases the fourth side from which the aligning pins project, being laid against the plate, as occasion requires; and the device as a whole being arranged at any desired angle to the edge of the angle 25 plate.

While I have illustrated and described with particularity only a single preferred form of my invention, I do not desire to be limited to the exact structural details thus 30 illustrated and described; but intend to cover all forms and arrangements which come within the terms employed in the definitions of my invention constituting the appended claims.

35 I claim:

1. A device of the character described, comprising two bars of extremely hard steel and screws connecting the same together to 40 form clamping jaws, said bars having flat upper faces lying in a common plane and

having flat inner side faces parallel with each other, said screws passing through the bars and being of such length that the outer side faces of the bars are left unobstructed when a thin piece of work is gripped in the 45 jaws.

2. A device of the character described, comprising two bars of extremely hard steel accurately rectangular in cross section, screws connecting the same together to form 50 clamping jaws, and a block of extremely hard steel having a square end and adapted to rest upon one of said bars, and means for detachably and adjustably securing said block upon the latter bar.

3. A device of the character described comprising two bars of hard steel uniformly accurately rectangular in cross section throughout their lengths, screws connecting the same together to form clamping jaws, 60 each bar having a groove extending longitudinally through its upper face, a block of hard steel having a square end, said block having on a side contiguous thereto a tongue adapted to fit into either of said grooves, and 65 means for adjustably securing said block to either of said bars.

4. A device of the character described comprising two bars of extremely hard steel accurately rectangular in cross section 70 throughout their lengths, and screws connecting the same together to form clamping bars, said screws passing through the bars and being of such length that the outer faces of the bars are left unobstructed when a 75 thin piece of work is gripped in the jaws.

In testimony whereof, I sign this specification.

THEODORE T. JANIS.
